UNITED STATES PATENT OFFICE

116,276

DESIGN FOR A BRACE CONNECTOR

Lawrence E. Baer, Attleboro, Mass., assignor to
Swank Products, Inc., a corporation of Delaware

Application July 18, 1938, Serial No. 78,554

Term of patent 14 years

To all whom it may concern:

Be it known that I, Lawrence E. Baer, a citizen of the United States of America, residing at Attleboro, county of Bristol, State of Massachusetts, have invented a new, original, and ornamental Design for a Brace Connector, of which the following is a specification, reference being had to the accompanying drawing, forming a part thereof.

Fig. 1 is a plan view of a brace connector showing my new design; and

Fig. 2 is a horizontal central sectional view of the same.

The predominating feature of the design con-

sists in the raised round knob or mound shown in relief in the center of the connector bar between the end rings; and the wide central partially circular enlargement in the connector bar in which the ends of the enlargement are joined with the rings by two neck portions each having concave side edges to form a smooth graceful curving contour of symmetrical form, the plane surfaces of which parts all lie in a single plane.

I claim:

The ornamental design for a brace connector, substantially as shown and described.

LAWRENCE E. BAER.
